AGE HARDENING OF STAINLESS STEELS WITH
NIOBium SILICIDES

William Rostoker and Clarence J. Carter, Chicago, Ill., assignors, by mesne assignments, to Atlas Steels Limited, Welland, Ontario, Canada, a corporation of Canada

No Drawing. Filed Mar. 23, 1959, Ser. No. 800,926
7 Claims. (Cl. 148—38)

This invention relates to stainless steels and more particularly to a method of age-hardening stainless steel and to the resultant age hardened alloy.

The full development of the potential market for stainless steel in the aircraft, consumer appliance and related fields requires stainless steel which in its as-quenched condition, has a sufficiently low hardness and high ductility for the steel to be worked readily in strip or sheet form and which can be age-hardened to provide sufficient hardness for adequate strength.

Stainless steels have previously been age-hardened using various carbides, aluminides and titanides. Titanium-aluminum, nickel-aluminum, and copper are a few of the many examples of precipitant that have been used for age-hardening chromium-nickel stainless steels. Similar precipitants have also been used in stainless steel in which part or all of the nickel has been replaced with manganese. The precipitants which have been referred to above each have various disadvantages such as hot shortness, lack of ductility in the as-quenched condition, lack of adequate hardness after age-hardening, poor welding characteristics and in some cases the precipitant causes depletion of the austenitic or ferritic matrix of chromium to an extent such that the corrosion and oxidation resistance suffer.

The object of this invention is to provide a new method of age-hardening stainless steel of the chromium, chromium-nickel, chromium-manganese or chromium-nickel-manganese type to give a stainless steel which combines various desirable properties as will be apparent from this description which follows.

A further object of this invention is to provide an age-hardened stainless steel of the chromium, chromium-nickel, chromium-manganese or chromium-nickel-manganese type which has a combination of desirable properties.

Another object of this invention is to provide an age-hardened stainless steel of the type referred to above in which age-hardening is achieved by the use of additives which are inexpensive and easy to handle.

Our invention involves the use of niobium-silicide as the age-hardening precipitant. The niobium may be added in any convenient form such as ferro-niobium. Similarly the silicon may be added in any convenient form such as ferro-silicon.

Niobium is used in an amount of 1.0-4% and silicon in an amount of 1.5-5%. The sum of the niobium and silicon additions should be between 3% and 7%. The ratio of niobium to silicon should be from 1:3 to 2:1. The silicides which are formed have the formulae NbSi_2 , Nb_3Si_5 . Additions in ratios substantially outside these limits would result in excess niobium or silicon residual in the austenite which would have the detrimental effect of reducing ductility. The best results where formability is important, namely low as-quenched hardness and com-

2

bined with high hardness after aging are obtained with 1.5-3% niobium and 3-5% silicon. The best ratio is about 1:2 of niobium to silicon and particularly good results are given by about 2% niobium with about 4% silicon. While low as-quenched hardness is important in the case of rolling stock, the higher as-quenched hardness characteristic of other formulations in accordance with this invention may be acceptable or even preferred for utilizations where formability is less important. Thus where 10 machinability and dimensional control are dominant requirements relatively high as-quenched hardness may be preferred to obtain the minimum dimensional change after machining. Similarly high as-quenched hardness is acceptable in the case of casting alloys.

15 The stainless steels with which this invention is concerned are chromium, chromium-nickel, chromium-nickel-manganese or chromium-manganese steels having 10-20% chromium, 0-10% nickel and 0-20% manganese where the sum of the nickel and manganese are not 20 in excess of the following:

$$\text{Percent Ni} + \frac{\text{Percent Mn}}{2} = 10\%$$

25 The structure of the steel produced in accordance with this invention is believed to be predominantly ferritic. A typical microstructure of an alloy in accordance with this invention appears to show a ferritic matrix with small 30 inclusions of austenite.

35 It is essential that the steels have a low carbon content as otherwise the niobium preferentially attaches to the carbon instead of forming a silicide. The carbon should therefore be less than 0.08%. Other elements which should be avoided are oxygen and nitrogen each of which interferes with the formation of the desired silicides. Oxygen should be less than 0.05% and preferably less than 0.01% and nitrogen should be less than 0.05% and preferably less than 0.005%. Other impurities usually found 40 in steel, such as phosphorus, sulphur and copper, may be present in the usual incidental amounts. It is permissible to include small amounts of alloying elements for special purposes, such as corrosion resistance or other properties, by adding molybdenum, tungsten or vanadium in amounts of up to about 5%. The alloying element which is added 45 should, however, be one which does not compete to any substantial extent with niobium to form silicides.

The aging temperature may range from about 800° F. to 1400° F. If the temperature is too low, hardening does not occur in a reasonable time. If the temperature is too high, no peak hardening is achieved and carbide precipitation is encouraged. It is preferred that aging be conducted at a temperature at which substantially the maximum hardness is developed. The time required for peak hardening varies from $\frac{1}{2}$ to 10 hours or more, according to the amounts of niobium and silicon and the temperature used for aging.

50 The following alloy is particularly effective in providing low as-quenched hardness and high aged hardness, namely 15-20% chromium, 0-4% nickel, 12-20% manganese

$$\left(\text{Percent Ni} + \frac{\text{Percent Mn}}{2} \text{ being less than } 10\% \right)$$

55 1.5%-3% niobium and 3-5% silicon. For example an

alloy of the composition 17Cr—2Ni—13Mn—2Nb—4Si will be advantageous.

The temperature used in the preliminary heat treatment prior to quenching should range from 1900° F. to 2200° F. The best solution treatment temperature to develop the particular properties desired may readily be ascertained for a particular alloy.

In preparing the experimental data given below, vacuum induction melting and casting techniques were used to give close control of the chemical composition and to avoid atmospheric contamination but other melting techniques can be used provided that excessive atmospheric contamination is avoided.

EXAMPLE 1

The analysis of the specimens used for the purpose of the example was:

Precipitating Agent	O	Mn	Si	Cr	Ni	Nb
0.5Nb—1Si	0.19	1.07	1.08	18.48	9.13	.49
1.0Nb—2Si	0.05	1.36	2.09	17.76	8.71	1.33
1.5Nb—3Si	0.045	1.20	3.15	17.55	8.58	1.75
2.0Nb—4Si	0.045	1.38	4.09	17.06	8.36	2.47
1.0Nb—1Si	0.04	1.34	1.01	18.09	8.62	1.25
2.0Nb—2Si	0.045	1.30	2.19	17.59	8.42	2.40
3.0Nb—3Si	0.05	1.26	3.38	17.06	8.10	3.40
2.0Nb—1Si	0.05	1.39	1.10	17.93	8.49	2.10
4.0Nb—2Si	0.06	1.26	2.28	16.60	8.06	4.89

Specimens of $\frac{1}{2}$ in. x 1 in. x 1 in. were machined from forged bars, solution treated at 2200° F. for one hour, water quenched and aged at 600° F., 800° F., 1000° F. and 1200° F. for various times. The results are shown in Table I.

EXAMPLE 2

Various chromium nickel steels were investigated using the same techniques as those described in connection with Example 1 with the results shown in Tables II to VI. These experiments indicate the results obtained by varying the nickel content. In each case the precipitant was niobium silicide, and the carbon was maintained at less than 0.08%.

We claim:

1. An age-hardened stainless steel, consisting essentially of 10-20% chromium, 0-10% nickel, 0-20% manganese, where the sum of the percentage of nickel and half the percentage of manganese is not in excess of 10%, 1.0-4% niobium, 1.5-5% silicon, the sum of the niobium and silicon additions being from 3% to 7%, less than 0.08% carbon, less than 0.05% oxygen, less than 0.05% nitrogen and remainder substantially all iron and permissible alloying elements, said permissible alloying elements being less than 5%, said niobium and silicon being predominantly in the form of a niobium silicide, said steel having been age-hardened by heat treatment substantially to its peak hardness.
